(57) **CLAIM**

I claim the ornamental design for a Christmas tree stand, as shown and described.

DESCRIPTION

FIG. 1 is a perspective view of a Christmas tree stand in accordance with a first embodiment of the present invention; FIG. 2 is a side view of the Christmas tree stand of FIG. 1; FIG. 3 is a top view of the Christmas tree stand of FIG. 1; FIG. 4 is a bottom view of the Christmas tree stand of FIG. 1;

FIG. 5 is a perspective view of a Christmas tree stand in accordance with a second embodiment of the present invention;

FIG. 6 is a side view of the Christmas tree stand of FIG. 5; FIG. 7 is a top view of the Christmas tree stand of FIG. 5; and, FIG. 8 is a bottom view of the Christmas tree stand of FIG. 5.

Each of the four sides of each embodiment of the Christmas tree stand is identical.
